MEANS FOR CONTROLLING THE RATE
OF SUPPLY OF LIQUID FUEL TO PRIME
MOVERSThomas Alfred Harris, Edgbaston, Birmingham,
England, assignor to Joseph Lucas Limited,
Birmingham, EnglandApplication May 31, 1951, Serial No. 229,010
In Great Britain June 6, 1950

3 Claims. (Cl. 138—46)

1

This invention relates to means for regulating the rate of supply of liquid fuel to a jet-engine, gas turbine or other prime mover, and has for its object to enable the said means to be controlled from a distance.

The invention comprises the combination of a throttle adapted to control the flow of liquid through an associated passage, a liquid actuated servo-mechanism for actuating the throttle, and electromagnetic means for controlling the servo-mechanism.

The accompanying drawing illustrates diagrammatically one embodiment of the invention.

Referring to the drawing, there is provided any convenient throttle as *a* adapted to control the rate of flow of liquid fuel supply through an orifice *b* to a pipe *c* which conveys the fuel from a pump *d* to the burner *e* of the prime mover.

The throttle is under the control of a fuel-actuated servo-mechanism. This comprises a cylinder *f* containing a piston *g* loaded by a spring *h*, the piston being connected to the throttle *a*. The ends of the cylinder are in communication with each other through a restricted orifice *i* which may be provided, as shown, in the piston, or in the cylinder wall, or in a pipe interconnecting the ends of the cylinder. The end of the cylinder *f* remote from the spring *h* acting on the piston *g* is adapted for connection with the inflow side of the throttle by a passage *j*. The other end of the cylinder is adapted for connection with a fuel supply tank *k* or the inlet side of the pump *d*, by way of a pipe or passage *m* under the control of one or more spring loaded vent valves arranged in parallel. In the example shown in the drawing, two such valves are shown, and indicated by *n* and *o* each is loaded by a spring *o*. Each valve is operable by an electromagnet *p*, the excitation of which can be controlled by a switch *q*. Also the vent passages *r* leading from the cylinder to the said valves are under the control of a piston valve *s* connected to or otherwise operable by the piston *g* of the servo-mechanism.

Assuming that it is required to supply liquid fuel to the burner at any one of three rates, two electromagnetically operable valves are provided as shown, and in this example the mode of action is as follows:

Starting with the throttle *a* at its position of maximum restriction of the orifice *b*, the quantity of fuel then supplied to the burner is at the minimum required, the fuel being supplied at a constant pressure by the pump *d*, which

2

pressure may be under the control of a relief valve (not shown). In this condition the piston valve *s* opens both of the vent passages *r* leading to the electro-magnetically operated vent valves, these being normally closed.

When it is required to increase the speed of the prime mover, the first of the two electro-magnetically operated vent valves is opened by excitation of the associated magnet. Liquid can now pass from the servo-motor cylinder, and the preponderant pressure acting on the piston *g* moves the latter in opposition to the spring *h* for increasing the flow past the throttle. When the throttle has been moved through an appropriate distance, the piston valve *s* interrupts the flow to the open electromagnetically operated valve, and so prevents further movement of the servo-piston and throttle.

When it is required to cause a still further increase of fuel flow past the throttle, the other electromagnetically operated valve is opened. The servo-mechanism then moves to the next position until arrested by a stop or by the closing (by the piston valve *s*), of the vent passage *r* leading to the second valve.

The invention is not, however, restricted to the above example, as it may be embodied in other forms. Thus, the throttle may be arranged in a system which is separate from the fuel system, and is provided with its own liquid circulating pump.

Having thus described my invention what I claim as new and desire to secure by Letters Patent is:

35. 1. Means for controlling the rate of supply of liquid fuel to a prime mover comprising, in combination, a throttle valve movable in a fuel supply passage for controlling fuel flow therein, a liquid actuated servo-mechanism including a cylinder and a piston operatively connected with the throttle valve for displacing the latter, a plurality of vent passages communicating with the cylinder, a valve controlling each of said vent passages, separate electromagnetic means for actuating each of said valves in succession, and a single valve member operatively connected with the piston and movable therewith upon successive actuation of the vent controlling valves to a series of positions for successively controlling the vent passages in a sense opposite to the control exercised by the separate valves upon actuation thereof, whereby the piston of the servo-mechanism is held in a position determined by the number of vent control valves actuated.
40. 2. Means according to claim 1, in which the
- 45.
- 50.

vent controlling valves are normally held in closed position and are opened by the electro-magnetic means, and the single valve member is constituted as a piston valve and is successively movable to close the vent passages which open into a single bore traversed by said piston valve.

3. Means according to claim 1, in which the servo-mechanism comprises a cylindrical chamber having at one end a liquid fuel inlet and an outlet controlled by the throttle valve, the other end of the chamber communicating with a bore coaxial with the chamber into which bore the vent passages open at spaced points, restricted orifice means affording communication between the two ends of the chamber which constitutes the cylinder of the servo-mechanism and the piston of which is connected to the throttle valve, a spring acting on the piston in the direction for moving the throttle valve to a position of

maximum obstruction of fuel flow, and a piston valve movable with the piston and constituting the single valve member, said piston valve being movable in the aforesaid coaxial bore for successively closing the ends of the vent passages therein, the separate valves controlling the vent passages being normally closed by springs and opened by actuation of the electromagnetic means.

THOMAS ALFRED HARRIS.
